US0D1102787S

(12) United States Design Patent (10) Patent No.: US D1,102,787 S
(45) Date of Patent: * Nov. 25, 2025

(54) OFFICE TABLE

(71) Applicant: UE FURNITURE CO., LTD, Huzhou (CN)

(72) Inventors: Pengfei Yu, Zhejiang (CN); Jin Ye, Zhejiang (CN); Zhengfu Ruan, Zhejiang (CN)

(73) Assignee: UE FURNITURE CO., LTD, Huzhou (CN)

() Term: 15 Years

(21) Appl. No.: 35/522,625

(22) Filed: Jul. 17, 2024

(80) Hague Agreement Data

Int. Filing Date: Jul. 17, 2024

Int. Reg. No.: DM/240805

Int. Reg. Date: Jul. 17, 2024

Int. Reg. Pub. Date: Oct. 11, 2024

(30) Foreign Application Priority Data

Jan. 17, 2024 (CN) 202430029685.7

(51) LOC (15) Cl. 06-03

(52) U.S. Cl.

USPC D6/643
